CLAIM

We claim the ornamental design for a pet feeding system, as shown and described.

DESCRIPTION

FIG. 1 is a top perspective view of a first embodiment of the pet feeding system according to our design, shown in an assembled condition;

FIG. 2 is an exploded top perspective view of the embodiment shown in FIG. 1;

FIG. 3 is an exploded bottom perspective view of the embodiment shown in FIG. 1;

FIG. 4 is a top view of the embodiment shown in FIG. 1;

FIG. 5 is a front view of the embodiment shown in FIG. 1;

FIG. 6 is a rear view of the embodiment shown in FIG. 1;

FIG. 7 is a right side view of the embodiment shown in FIG. 1, a left side view being a mirror image of the right side view;

FIG. 8 is a top perspective view of a stand used in the embodiment shown in FIG. 1;

FIG. 9 is a top view of the stand shown in FIG. 8;

FIG. 10 is a front view of the stand shown in FIG. 8;

FIG. 11 is a rear view of the stand shown in FIG. 8;

FIG. 12 is a left side view of the stand shown in FIG. 8, a right side view being a mirror image of the left side view;

FIG. 13 is a side-to-side sectional view taken through a center of the stand shown in FIG. 8;

FIG. 14 is a front-to-rear sectional view taken through a center of the stand shown in FIG. 8;

FIG. 15 is a top perspective view of a mat used in the embodiment shown in FIG. 1;

FIG. 16 is a top view of the mat shown in FIG. 15;

FIG. 17 is a front view of the mat shown in FIG. 15;

FIG. 18 is a rear view of the mat shown in FIG. 15;

FIG. 19 is a right side view of the mat shown in FIG. 15, a left -side view being a mirror image of the right side view;

FIG. 20 is a front-to-rear sectional view taken through a center of the mat shown in FIG. 15;

FIG. 21 is a side-to-side sectional view taken through a center of the mat shown in FIG. 15;

FIG. 22 is a top perspective view of a second embodiment of the pet feeding system according to our design, shown in an assembled condition;

FIG. 23 is a top perspective exploded view of the embodiment shown in FIG. 22;

FIG. 24 is a bottom perspective exploded view of the embodiment shown in FIG. 22;

FIG. 25 is a top view of the embodiment shown in FIG. 22;

FIG. 26 is a front view of the embodiment shown in FIG. 22;

FIG. 27 is a rear view of the embodiment shown in FIG. 22;

FIG. 28 is a right side view of the embodiment shown in FIG. 22, a left side view being a mirror image of the right side view;

FIG. 29 is a top perspective view of a stand used in the embodiment shown in FIG. 22;

FIG. 30 is a top view of the stand shown in FIG. 29;

FIG. 31 is a front view of the stand shown in FIG. 29;

FIG. 32 is a rear view of the stand shown in FIG. 29;

FIG. 33 is a left side view of the stand shown in FIG. 29, a right side view being a mirror image of the left side view;

FIG. 34 is a side to side sectional view of the stand shown in FIG. 29;

FIG. 35 is a front-to-rear sectional view of the stand shown in FIG. 29;

FIG. 36 is a top perspective view of a mat used in the embodiment shown in FIG. 22;

FIG. 37 is a top view of the mat shown in FIG. 36;

FIG. 38 is a front view of the mat shown in FIG. 36;

FIG. 39 is a rear view of the mat shown in FIG. 36;

FIG. 40 is a right side view of the mat shown in FIG. 36, a left side view being a mirror image of the right side view;

FIG. 41 is a front-to-rear sectional view taken through a center of the mat shown in FIG. 36;

FIG. 42 is a side-to-side sectional view taken through a center of the mat shown in FIG. 36;

FIG. 43 is a top perspective view of either of two bowls used in the embodiment shown in FIG. 22;

FIG. 44 is a top view of the bowl shown in FIG. 43;

FIG. 45 is a right side view of the bowl shown in FIG. 43, a left side view being a mirror image of the right side view;

FIG. 46 is a rear view of the bowl shown in FIG. 43;

FIG. 47 is a front view of the bowl shown in FIG. 43;

FIG. 48 is a bottom view of the bowl shown in FIG. 43;

FIG. 49 is a side-to-side sectional view taken substantially along line 49-49 of FIG. 44;

FIG. 50 is a front-to-rear sectional view taken substantially along line 50-50 of FIG. 44;

FIG. 51 is a top perspective view of a third embodiment of the pet feeding system according to our design, shown in an assembled condition;

FIG. 52 is a top perspective exploded view of the embodiment shown in FIG. 51;

FIG. 53 is a bottom perspective exploded view of the embodiment shown in FIG. 51;

FIG. 54 is a top view of the embodiment shown in FIG. 51;

FIG. 55 is a front view of the embodiment shown in FIG. 51;

FIG. 56 is a rear view of the embodiment shown in FIG. 51;

FIG. 57 is a right side view of the embodiment shown in FIG. 51, a left side view being a mirror image of the right side view;

FIG. 64 is a front-to-rear sectional view taken through a center of the stand shown in FIG. 58;

FIG. 65 is a top perspective view of a mat used in the embodiment shown in FIG. 51;

FIG. 66 is a top view of the mat shown in FIG. 65;

FIG. 67 is a front view of the mat shown in FIG. 65;

FIG. 68 is a rear view of the mat shown in FIG. 65;

FIG. 69 is a right side view of the mat shown in FIG. 65, a left side view being a mirror image of the right side view;

FIG. 70 is a front-to-rear sectional view taken through a center of the mat shown in FIG. 65;

FIG. 71 is a side-to-side sectional view taken through a center of the mat shown in FIG. 65;

FIG. 72 is a top perspective view of either of two bowls as used in the embodiment shown in FIG. 53 and as used in the embodiment shown in FIG. 80;

FIG. 73 is a top view of the bowl shown in FIG. 72;

FIG. 74 is a right side view of the bowl shown in FIG. 72, a left side view thereof being a mirror image of the right side view;

FIG. 75 is a rear view of the bowl shown in FIG. 72;

FIG. 76 is a front view of the bowl shown in FIG. 72;

FIG. 77 is a bottom view of the bowl shown in FIG. 72;

FIG. 78 is a side-to-side sectional view taken substantially along line 78-78 of FIG. 73;

FIG. 79 is a front-to-rear sectional view taken substantially along line 79-79 of FIG. 73;

FIG. 80 is a top perspective view of a fourth embodiment of our design, shown in an assembled condition;

FIG. 81 is an exploded top perspective view of the embodiment shown in FIG. 80;

FIG. 82 is an exploded bottom perspective view of the embodiment shown in FIG. 80;

FIG. 83 is a top view of the embodiment shown in FIG. 80;

FIG. 84 is a front view of the embodiment shown in FIG. 80;

FIG. 85 is a rear view of the embodiment shown in FIG. 80;

FIG. 86 is a right side view of the embodiment shown in FIG. 80, a left side view being a mirror image of the right side view;

FIG. 87 is a top perspective view of a stand used in the embodiment shown in FIG. 80;

FIG. 88 is a top view of the stand shown in FIG. 87;

FIG. 89 is a front view of the stand shown in FIG. 87;

FIG. 90 is a rear view of the stand shown in FIG. 87;

FIG. 91 is a left side view of the stand shown in FIG. 87, a right side view being a mirror image of the left side view;

FIG. 92 is a side-to-side sectional view taken through a center of the stand shown in FIG. 87;

FIG. 93 is a front-to-rear sectional view taken through a center of the stand shown in FIG. 87;

FIG. 94 is a top perspective view of a mat used in the embodiment shown in FIG. 80;

FIG. 95 is a top view of the mat shown in FIG. 94;

FIG. 96 is a front view of the mat shown in FIG. 94;

FIG. 97 is a rear view of the mat shown in FIG. 94;

FIG. 98 is a right side view of the mat shown in FIG. 94, a left side view being a mirror image of the right side view;

FIG. 99 is a front-to-rear sectional view taken through a center of the mat shown in FIG. 94;

FIG. 100 is a side-to-side sectional view taken through a center of the mat shown in FIG. 94;

FIG. 101 is a top perspective view of a fifth embodiment of our design, shown in an assembled condition;

FIG. 102 is an exploded top perspective view of the embodiment shown in FIG. 101;

FIG. 103 is an exploded bottom perspective view of the embodiment shown in FIG. 101;

FIG. 104 is a top view of the embodiment shown in FIG. 101;

FIG. 105 is a front view of the embodiment shown in FIG. 101;

FIG. 106 is a rear view of the embodiment shown in FIG. 101;

FIG. 107 is a right side view of the embodiment shown in FIG. 101, a left side view thereof being a mirror image of the right side view;

FIG. 108 is a top perspective view of a stand used in the embodiment shown in FIG. 101;

FIG. 109 is a top view of the stand shown in FIG. 108;

FIG. 110 is a front view of the stand shown in FIG. 108;

FIG. 111 is a rear view of the stand shown in FIG. 108;

FIG. 112 is a left side view of the stand shown in FIG. 108, a right side view thereof being a mirror image of the left side view;

FIG. 113 is a side-to-side sectional view taken through a center of the stand shown in FIG. 108;

FIG. 114 is a front-to-rear sectional view taken through a center of the stand shown in FIG. 108;

FIG. 115 is a top perspective view of a mat used in the embodiment shown in FIG. 101;

FIG. 116 is a top view of the mat shown in FIG. 115;

FIG. 117 is a front view of the mat shown in FIG. 115;

FIG. 118 is a rear view of the mat shown in FIG. 115;

FIG. 119 is a right side view of the mat shown in FIG. 115, a left side view thereof being a mirror image of the right side view;

FIG. 120 is a front-to-rear sectional view taken through a center of the mat shown in FIG. 115;

FIG. 121 is a side-to-side sectional view taken through a center of the mat shown in FIG. 115;

FIG. 122 is a top perspective view of either of two bowls used in the embodiment shown in FIG. 101 and also used in the embodiment shown in FIG. 130;

FIG. 123 is a top view of the bowl shown in FIG. 122;

FIG. 124 is a right side view of the bowl shown in FIG. 122, a left side view thereof being a mirror image of the right side view;

FIG. 125 is a rear view of the bowl shown in FIG. 122;

FIG. 126 is a front view of the bowl shown in FIG. 122;

FIG. 127 is a bottom view of the bowl shown in FIG. 122;

FIG. 128 is a side-to-side sectional view taken substantially along line 128-128 of FIG. 123;
FIG. 129 is a front-to-rear sectional view taken substantially along line 129-129 of FIG. 123;
FIG. 130 is a top perspective view of a sixth embodiment of our design, shown in an assembled condition;
FIG. 131 is an exploded top perspective view of the embodiment shown in FIG. 130;
FIG. 132 is an exploded bottom perspective view of the embodiment shown in FIG. 130;
FIG. 133 is a top view of the embodiment shown in FIG. 130;
FIG. 134 is a front view of the embodiment shown in FIG. 130;
FIG. 135 is a rear view of the embodiment shown in FIG. 130;
FIG. 136 is a right side view of the embodiment shown in FIG. 130, a left side view thereof being a mirror image of the right side view;
FIG. 137 is a top perspective view of a stand used in the embodiment shown in FIG. 130;
FIG. 138 is a top view of the stand shown in FIG. 137;
FIG. 139 is a front view of the stand shown in FIG. 137;
FIG. 140 is a rear view of the stand shown in FIG. 137;
FIG. 141 is a left side view of the stand shown in FIG. 137, a right side view thereof being a mirror image of the left side view;
FIG. 142 is a side-to-side sectional view taken through a center of the stand shown in FIG. 137;
FIG. 143 is a front-to-rear sectional view taken through a center of the stand shown in FIG. 137;
FIG. 144 is a top perspective view of a mat used in the embodiment shown in FIG. 130;
FIG. 145 is a top view of the mat shown in FIG. 144;
FIG. 146 is a front view of the mat shown in FIG. 144;
FIG. 147 is a rear view of the mat shown in FIG. 144;
FIG. 148 is a right side view of the mat shown in FIG. 144, a left side view thereof being a mirror image of the right side view;
FIG. 149 is a front-to-rear sectional view taken through a center of the mat shown in FIG. 144;
FIG. 150 is a side-to-side sectional view taken through a center of the mat shown in FIG. 144;
FIG. 151 is a top perspective view of a seventh embodiment of our design, shown in an assembled condition;
FIG. 152 is an exploded top perspective view of the embodiment shown in FIG. 151;
FIG. 153 is an exploded bottom perspective view of the embodiment shown in FIG. 151;
FIG. 154 is a top view of the embodiment shown in FIG. 151;

FIG. 155 is a front view of the embodiment shown in FIG. 151;
FIG. 156 is a rear view of the embodiment shown in FIG. 151;
FIG. 157 is a right side view of the embodiment shown in FIG. 151, a left side view thereof being a mirror image of the right side view;
FIG. 158 is a top perspective view of a stand used in the embodiment shown in FIG. 151;
FIG. 159 is a top view of the stand shown in FIG. 158;
FIG. 160 is a front view of the stand shown in FIG. 158;
FIG. 161 is a rear view of the stand shown in FIG. 158;
FIG. 162 is a left side view of the stand shown in FIG. 158, a right side view thereof being a mirror image of the left side view;
FIG. 163 is a side-to-side sectional view taken through a center of the stand shown in FIG. 158;
FIG. 164 is a front-to-rear sectional view taken through a center of the stand shown in FIG. 158;
FIG. 165 is a top perspective view of a mat used in the embodiment shown in FIG. 151;
FIG. 166 is a top view of the mat shown in FIG. 165;
FIG. 167 is a front view of the mat shown in FIG. 165;
FIG. 168 is a rear view of the mat shown in FIG. 165;
FIG. 169 is a right side view of the mat shown in FIG. 165, a left side view thereof being a mirror image of the right side view;
FIG. 170 is a front-to-rear sectional view taken through a center of the mat shown in FIG. 165;
FIG. 171 is a side-to-side sectional view taken through a center of the mat shown in FIG. 165;
FIG. 172 is a top perspective view of either of two bowls used in the embodiment shown in FIG. 151;
FIG. 173 is a top view of the bowl shown in FIG. 172;
FIG. 174 is a right side view of the bowl shown in FIG. 172, a left side view thereof being a mirror image of the right side view;
FIG. 175 is a rear view of the bowl shown in FIG. 172;
FIG. 176 is a front view of the bowl shown in FIG. 172;
FIG. 177 is a bottom view of the bowl shown in FIG. 172;
FIG. 178 is a side-to-side sectional view taken substantially along line 178-178 of FIG. 173; and,
FIG. 179 is a front-to-rear sectional view taken substantially along line 179-179 of FIG. 173.
The bottoms of the stands and mats depicted in the various embodiments of our design are unadorned and form no portion of the claimed design.
The broken lines depict portions of the pet feeding system that form no part of the claimed design.
